UNITED STATES PATENT OFFICE.

CLARENCE A. BISHOP, OF NEW YORK, N. Y.

CALCULATING APPARATUS.

1,094,514.

Specification of Letters Patent. Patented Apr. 28, 1914.

Application filed June 21, 1913. Serial No. 775,014.

To all whom it may concern:

Be it known that I, CLARENCE A. BISHOP, a citizen of the United States, residing in the city of New York, borough of Brooklyn, county of Kings, and State of New York, have invented a certain new and useful Calculating Apparatus, of which the following is a specification.

This invention is an apparatus for effecting calculations, the same being intended, more particularly, for use in connection with insertible time cards for determining elapsed time and with insertible time and wage cards for calculating automatically the value of workmen's wages for variable periods at fixed rates per hour.

An apparatus embodying the invention is intended to receive the time card if elapsed time only is to be calculated, or the wage and time card if the time and wage value are to be calculated, such card or cards being provided with an appropriate scale or scales, and said card or cards being insertible into the machine at certain periods or intervals of time, as for example when the workman begins work and completes work on a particular job assigned to him. The machine is of such construction that the workman cannot interfere with its operation, such as by inserting a tool or wire into it, without running the risk of detection, for the reason that the moving parts are incased or housed to preclude access thereto; but to prevent movement of a time-driven member by manipulation of the card to be operated upon, means are provided for locking such time-driven member, such locking means being independent of the time-operated mechanism and being brought into action solely by manual manipulation of the card.

A machine embodying the invention employs, among other things, a card marking member and a card positioning member, one being movable relative to the other by the time-operated mechanism. It is preferred to use a punching or recessing device as the card marking member, said card punching or recessing device being positioned for manual operation at any time by the workman.

The machine of this application is intended, more particularly, for carrying out the method disclosed in my copending application filed June 9, 1910, Serial No. 565,959, which eventuated in Patent No.

1,065,501 June 24, 1913; of which method application and patent the present application is in part a division and more particularly as to that feature thereof which embodies the recessing device adapted to punch in a card a recess of a particular form or shape, a time train, a movable guide operated or advanced by the time train and having the same form in horizontal cross section as the recess punched in the card by the recessing device but in reverse thereto, so that when the card is punched at the end of a given time and reversed; the said guide will fill the recess.

According to one part of this invention, the card is inserted twice into the machine, and is punched or recessed a like number of times, one of such recesses or punches being produced in the card at the time the workman starts work on the assigned job, and the other at the time of completing work on the job. To indicate on the card the time of starting the work and the elapsed time, and to insure that the card shall at the second punching operation be inserted into the machine in a proper manner to effect the desired calculation, the punches or recesses initially and ultimately produced in the card are, preferably, of beveled or tapering form, and they are reversed to each other. Accordingly, in a preferred form, the punch mechanism is provided with a beveled operating punch member to produce a beveled recess in the card, whereas the card retaining member is provided with a beveled exposed card engaging portion reversely positioned to the beveled operating punch of said punch mechanism, whereby after the card is first punched to produce the beveled recess at the beginning of the work, said card must be reversed prior to the second punching operation to indicate the completion of the work, which reversal of the card enables it to be positioned at the second punching operation for the beveled edged recess first punched therein to register and contact properly with the beveled card-engaging portion of the card-retaining member.

In the apparatus to be hereinafter described as a preferred embodiment of the invention, the card punching member is normally stationary, whereas the card positioning member is movable, by clock mechanism of one form or another. The card retaining member embodies a moving part

and a plurality of card-engaging elements movable with said moving part, said card engaging elements being positioned so that a card to be operated upon may be inserted into the machine for engagement with said elements, whereby the position of the card with respect to the punching mechanism is determined with accuracy.

As before stated, a distinctly novel feature 10 consists of means independent of the time operated mechanism for locking the card retaining member, said locking means being operable by manipulation of the card subsequent to its insertion. In a preferred 15 form of said locking means, the card engaging elements of the card positioning member are pivoted to the moving part and they are provided with means for frictionally clutching them to the guideway for 20 said moving part. Thus, upon the insertion of the card in a proper manner, for the purpose of punching it, the card engaging elements are free from clutching engagement with the guideway, but should the 25 workman manipulate the card in any way so as to shift the normally inaccessible card positioning member for giving an unaccrued increase in wages, then the displacement of the card, to even a slight degree, so 30 acts on one or the other of the card engaging elements as to lock the card positioning member from movement, thus effectively and automatically frustrating the workman's surreptitious effort to secure an increased wage accounting.

The time-operated card engaging member is movable relative to the punching device at predetermined intervals and for a predetermined distance, such distances corresponding to the divisions of the inserted 40 card, so that the recesses will be produced in a proper manner in the card. The total distance traveled by the card positioning member is equal to the length of the scale on the 45 card, so as to represent ordinarily the working hours of a day.

In a preferred form, the invention embodies means for automatically releasing the card positioning member from the time 50 train at the completion of the hours necessary to cover a working day, and for returning said card positioning member to a starting position, but when it is desired to use the machine for calculating over-time, 55 means are provided whereby the same mechanism may be used to produce recesses in a card for denoting overtime.

The means for returning the card positioning member to a starting position is a 60 drum actuated by a spring, the latter being placed under tension by the operation of the time train main spring, said drum being held fast to one of the time train arbors by a notched wheel engaged by a pawl, but when 65 the pawl and wheel have turned a prede-

termined distance, then the pawl is disengaged from the notched wheel and the spring drum becomes effective in automatically returning the card positioning member to the starting position. To adapt the mechanism 70 for denoting over-time work on cards, i. e. for the hours which elapse between the ending of the working day and the beginning of the next, a simple mechanism is employed 75 in connection with said spring drum, notched wheel and pawl. Said mechanism is embodied in a second pawl and a second wheel, said second pawl being actuated by the second wheel so as to make the drum fast with the arbor of the time train, whereby the second pawl is effective in imparting the motion of the time train to the card retaining member for operating the latter in the interval denoting over-time and before the next 80 regular day begins, then the second pawl is 85 automatically thrown out of operative position and the first named pawl is at the proper interval engaged with the notched wheel to place the machine in readiness for use during the regular working hours.

The invention embodies means for marking the inserted card so as to detect improper insertion of said card in the machine at any one of the punching operations.

Other features of the inventions and the 90 advantages thereof will appear from the following detailed description.

In the drawings, Figure 1 is a sectional plan view of a calculating machine embodying the invention, certain parts being broken 100 away and in section to show some of the mechanism contained within a casing. Fig. 2 is an inverted bottom plan view illustrating a part of the card positioning member and a part of the time train cooperating with said card positioning member. Fig. 3 is a front view, partly in vertical section, of the machine illustrated in Fig. 1. Fig. 4 is a cross section on the line 4-4 of Fig. 3. Fig. 5 is an enlarged detail view of certain 110 parts composing the card positioning member, illustrating one of the card engaging elements in a normal position by full lines, whereas the dotted lines illustrate a shifted position of the card engaging element for 115 the purpose of locking or clutching said element to preclude movement of the card retaining member. Fig. 6 is a fragmentary detail view of the punch. Fig. 7 illustrates diagrammatically the position of the card 120 positioning member, the punch, and a card, the latter being inserted for the first time into position relative to the card positioning member and a punch for the purpose of producing the first recess in the card. Fig. 7 is a plan view of the card shown in Fig. 7 after the two recesses shall have been punched therein, said figure illustrating certain data on the face of the card. Figs. 9, 10 and 11 are views of the mechanism em- 130

bodied in the machine when the latter is to be used for punching overtime in the cards in addition to the use of the machine for the regular working hours during the day.

5 The base or casing A is provided with a chamber *a* within which is contained certain of the operating devices. The base or casing may be of any suitable form and size; as shown, it is an oblong hollow structure 10 provided with cushion feet *a'*.

In the top of the base is a longitudinal slot *b*, and over the slot is positioned a cover B, the latter extending the full length of the base. The cover is spaced with respect 15 to the top of the base, and at its front edge the cover is free from contact with the top so as to provide an opening *b'* through which a marginal portion of a card is adapted to be inserted. The rear portion of 20 the cover plate is intended to contact with the top so as to form an abutment for engagement by the edge of the card when the latter is inserted below the cover plate and across the slot *b* in the casing, and this cover 25 plate precludes direct access to the card retaining member or to the mechanism contained within chamber *a* of the base.

In the machine shown, the punching mechanism is normally stationary with respect to the base upon which said punching mechanism is mounted, whereby the punching mechanism is exposed for convenient operation by hand. Any suitable form of 30 punch mechanism may be employed, but, as shown more particularly in Fig. 4, the punch mechanism embodies a post *c*, a plunger *c'* and a spring *c''*. The post *c* is fixed in any suitable way to the top of the base, said post being constructed and positioned 35 to overhang the cover plate B, and within this post is provided a vertical passage *c³*, within which operates plunger *c'*. The plunger is shown as having a suitable exposed operating head *c⁴*, and around said 40 plunger is positioned the coiled spring *c''*. The lower part of the spring rests upon a shoulder provided in vertical passage *c³* of the post, whereas the upper part of the spring acts against a shoulder provided below the operating head *c⁴*, said spring acting, mainly, to support the plunger in a raised position. The plunger is prevented 45 from turning within the post by a stop pin *c⁵*, the latter serving, also, as a means for arresting the upward movement of the plunger under the impulse of spring *c''*. The plunger operates in an aperture provided in the cover plate (as shown in Fig. 4), and at the lower part of this plunger is a punch or 50 die C, shown more particularly in Fig. 6. The punch or die is in alignment vertically with a female die D, shown in Fig. 4 as being countersunk in the top of the base so that the card may slip over said female die, 55 the latter being at one side of a vertical

slot *b*, and in register with said female die D is a discharge tube *d* leading into or through the base, for the purpose of discharging the cuttings which are produced by the operation of punch or die C upon the 60 cards inserted into the machine.

The card retaining member shown in the preferred embodiment of the invention is movable relative to the punch member or mechanism, for which purpose a time train or clock mechanism is employed to impart movement to said card retaining member, the details of which mechanisms will now be described.

The card retaining member is shown in Figs. 1 to 5, inclusive, as embodying a stationary track member *e*, a movable member *e'* slidably fitted to the track member, and a plurality of card engaging elements E E'. The stationary track member *e* is shown as 80 a rod or bar occupying a horizontal position within chamber *a* and extending the length of base A, the end portions of said rod being supported in end walls of the base, as illustrated in Fig. 3, whereby the track member occupies a horizontal stationary position within the base. The moving part *e'* consists of a rod or bar suspended below the track member and having upstanding forked or bifurcated end portions *e²*, said end portions of the rod or bar embracing the track member *e* for the purpose of sliding freely thereon. The card engaging elements E E' are supported on or carried by the forked end portions of movable part *e'*, 85 and these elements E E' extend upwardly from the track rod so that the upper portions of said elements E E' pass through slot *b* in the top of the base, the extreme upper end portion of said element E' extending upwardly into a guide channel *e³* provided in under side of cover plate B, see Fig. 4. The upstanding card engaging element E is provided with a part *f* adapted for engagement with an indicating element 90 of the card to be inserted, this part *f* being correspondingly shaped to the male die or punch, but being positioned reversely thereto, for a purpose which will presently appear. This part *f* of the card engaging element E is in the form of a finger provided with a raised shoulder, said finger extending rearwardly from the slot *b* and the raised shoulder being in the same longitudinal plane as the male die or punch, see Fig. 1. While various forms of punch and the card engaging part of element E may be employed for the purposes of this invention, I use a male die or punch with a beveled side, see Figs. 1 and 6, whereas the card engaging finger *f* is provided, also, with a beveled side, but the bevel of the male die or punch is reversed to the bevel of the card engaging finger. As shown in Fig. 6, the male die or punch is a four-sided figure 100 95 105 110 115 120 125 130

with an inclined side joining two parallel sides. Similarly, the card engaging finger f is a four-sided figure with an inclined side connecting the two parallel sides, but the inclination of the inclined side of the male die or punch is reversed to that of the card engaging finger. When the card is first inserted into the machine and the punch is operated a recess with a beveled side is cut in the card. Now when the card is inserted for the second punching or recessing operation, said card is preferably reversed in position, that is, it must be turned end for end and the face must be placed downward upon the top of the base. This reversal of the card is for the purpose of bringing the first punch mark or recess therein into register with the card engaging finger, the latter fitting in the punch or recess of the card so that the recess will fit accurately to the shape of said card engaging finger; in other words, the card cannot be inserted at the second punching or recessing operation unless the first punch or recess has been initially produced in the card, and said card is reversed in order to bring the said first punch or recess into register with the card engaging finger. The space or distance between the card engaging elements E E' is equal substantially to the length of the card to be used, and to enable the card to be properly positioned in the card retaining member it is preferred to employ a card of the form shown in Figs. 7 and 8 wherein the card X is provided with a permanent index which is in the form of a notch x produced in one corner of said card.

Each element E E' is provided with a foot g , the width of which exceeds the width of the element, and this foot is recessed so as to produce two contact points g' adapted to frictionally engage with the upper side of the track rod E . The foot g' of each member is fitted within the upper bifurcated part of one end piece e^2 of the suspended rod or bar e' , and said foot g and the bifurcated end piece e^2 are connected by a pivotal pin g^2 , the latter passing through jaws provided by end piece e^2 and through the foot g centrally of the latter. It will be noted that the card engaging elements E E' are positioned at the respective ends of rod or bar e' , and that the foot pieces g of said elements E E' are connected pivotally with the bifurcated ends e^2 , said foot pieces g having reduced contact points g' adapted to engage frictionally with the upper face of fixed track bar e . The elements E E' operate to suspend rod or bar e' below the track rail e in such manner that the rod or bar and the elements E E' are free to move lengthwise of the track rail and with a minimum amount of friction. The engagement of the points g' on the upstanding elements E E' with the track rail retain said

elements normally in proper positions for the card to be inserted between said elements and in contact or engagement therewith, but should any attempt to manipulate or change the position of the card take place by the act of the workman, then the operation of shifting the card in one direction or the other will turn the element E or E' on the pivot g^2 into the inclined position, shown by dotted lines in Fig. 5, whereby the change in position of the element E or E' will bring one contact point g' of the card engaging element into forcible engagement with the track rod, as a result of which the frictional contact between the point g' of the card engaging element with the track rod acts as a lock in precluding any movement of the card retaining member in the direction of the length of said track rod. Briefly stated, the foot g of each card engaging element acts as a friction lock when said element is shifted by manipulation of the card, which lock precludes any movement of the card retaining member should an attempt be made by the workman to increase the value of the time or wages indicated by the record on the card. It may be said that the bar or rod e' acts as a carriage for the card engaging elements, the latter operating to suspend said carriage from the track rod. The frictional contact between the feet g of the card engaging elements with the track rod may be adjusted by movement of certain screws g^3 which are screwed into tapped openings provided in the rod or bar e' and adapted for frictional engagement with the under side of the track rod. By turning these screws in one direction the frictional contact between the points g' with the rod or bar may be tightened so as to preclude movement of the carriage and elements E E' mounted thereon, but, obviously, sufficient slack or play should be permitted to secure freedom in the movement of the carriage and said elements E E' on the track rail e .

Any form of time train may be employed for communicating motion to the card retaining member, and this time train is provided with an escapement which is adapted for control by a master clock so that a series of the recording apparatus may be used on a single circuit controlled by said master clock, or if desired the time train of each recorder may be controlled individually by a device of any suitable construction. As shown, the time train F is carried by a suitable frame F' attached to the top of the base, and within this frame is supported the main spring G and a series of arbors h h' provided with gears arranged to transmit the motion of the spring and controlled by the pallet wheel h' of an escapement mechanism. The escapement lever h^2 is pivoted at h^3 so that the tooth of the escapement

will engage with a tooth of the pallet wheel h' , and this escapement lever is provided with an armature i of an electromagnet I , the latter being in an electric circuit controlled by the master clock, the conductors of said circuit being indicated at i' .

Mounted loosely on the lower part of one arbor, such as h , of the time train is a spool J adapted to turn independently of the arbor. Said spool is provided at one end with a gear pinion j , and at its other end with a disk j' , the latter being provided with a notch or tooth j^2 . The gear j' of the spool is in mesh directly with teeth j^3 of a rack bar J' , the latter being fixedly secured to the end portion c^2 of the carriage bar. The carrying arm K is secured rigidly to the lower extremity of arbor h by a screw k' so that the arm K will rotate with the post, and on this arm K is mounted a feedpawl K' by a pin k^2 . This pawl is pressed by a spring k^3 into the notch j^2 of wheel j' , and the pawl thus operates to make the wheel fast with the arbor, whereby the motion of the time train transmitted through arbor h is communicated by the pawl and the notched disk to the gear j for the purpose of moving rack J' and the carriage, so as to impel the card engaging elements $E E'$ for a predetermined distance and at predetermined intervals of time. When the disk and the pawl make one complete revolution, the heel l of said pawl engages with a fixed post l' , thereby disengaging the nose of the pawl from the notch in the wheel j' . At this time the power of a return spring L becomes effective in turning spool J , the notched disk j' and gear j in a backward direction for the purpose of moving the carriage and the card engaging elements back to a starting position. The spring L is coiled around the spool, one end of the spring is attached to said spool and the other end of the spring is anchored on the fixed pin l' . When the carriage is in an operative position and is movable under the action of the time train controlled by the escapement so as to travel in the direction of the arrow of Fig. 1, the power of the main spring G impels the time train and the carriage, and it is available, also, in placing the spring L under tension; but upon the disengagement of pawl K' from the notch j^2 of wheel j' , then the recoil of spring L acting upon the spool J turns the spool, disk j' , and gear j in a reverse direction, for the purpose of returning the carriage and elements $E E'$ to starting position. When the pawl is disengaged from the notch in the wheel, the nose of said pawl is pressed by the spring into contact with the peripheral edge of said wheel, and thus the pawl is retained in position to enter the notch in the wheel at the proper time.

Should the workman attempt to manipu-

late the card for the purpose of securing an unearned amount of time or wages, by placing the card improperly in the machine, means are provided for producing on the card an indication that said card was improperly placed within the machine. This means for detecting an unwarranted attempt on the part of the workman will be referred to as a detector device, and in a preferred form it is operated by the punch carrying plunger so as to produce perforations in a certain part of the card. The detector element is embodied in a yieldable bar M housed or contained within a recessed part m of cover B . This detector bar is provided with depending pins or studs m' arranged to enter apertures n provided in the top of the casing. The detector bar is adapted to be depressed when the plunger is operated to punch or recess the card by a stem N , the latter being shown in Figs. 3 and 4 as attached to the plunger head c^4 , and the lower end of said plunger stem being adapted to pass through an opening n' provided in cover plate B at a point directly above the detector bar M . The detector bar is composed, preferably, of spring steel so that it will raise or lift itself above the path of the card when the latter is inserted below the cover and across slot b . Now, when the punch plunger is forcibly depressed, stem N will move downwardly and act upon the detector bar so as to force the latter toward the card, whereby pins m' will perforate the card along a certain line provided on said card, the material cut out of the card passing through the openings n into chamber a of the base. When the card is properly inserted two or more pins m' will punch perforations in the card along a certain predetermined line, but should the card be turned at an angle or improperly positioned and the punch mechanism operated, then the pins m' of the detector bar N will punch holes in the card not along the predetermined line, thus affording an indication that the workman has attempted to secure unearned time or wage value by improperly positioning the card in the machine.

The card shown in Figs. 7 and 8 is one of several kinds which may be used, said card having suitable spaces x' for the reception of data pertaining to the date, the job number, the workman's name and number, the operation to be performed, and various other printed matter. In addition to the notch x and the spaces x' for receiving the desired data, the card is provided with a scale z denoting elapsed time, said scale being divided into hours and fractions thereof corresponding to the working hours of the day, and said scale reading progressively from the notched corner x substantially to the opposite end of the card. In

addition to the foregoing elapsed time scale, the card may or may not be provided with a second scale z' having numerals or other data indicating the starting time. Furthermore, the card may or may not be provided with a scale having numerals or other data to represent wages to be paid to the workman based upon the time engaged upon a particular job and at a fixed rate per hour.

10 The wage scale should be divided into fractions corresponding to the divisions of the elapsed time scale, the two scales being in parallel columns. In addition to the foregoing scale or scales, the card is provided with an indicating line z^2 along which the card may be punched by the operation of the pins m' of detector bar M, two of said punch marks being indicated by the reference character z^3 .

20 The operation of the invention as thus far described is as follows: The main spring G is wound so as to place it under tension, and assuming that the carriage is at the starting position for the card receiving elements to occupy the relation to the punching mechanism illustrated in full and dotted lines in Figs. 1 and 3, the pawl K' is pressed by the spring for the nose of said pawl to enter the notch j^2 of wheel j' , whereby the 25 time train acts through the arbor h and arm K to impart movement to the pawl and the notched wheel for the purpose of turning the gear j, and thereby imparting movement to the carriage and the card retaining elements thereon. With the parts in the starting position at the beginning of a working day, say at 7 a. m., the workman inserts a 30 card into the machine in the following manner: The card is turned face down to start, or in the position shown in Fig. 7, the 35 notched corner z of the card engaging with the finger f of element E, whereas the opposite edge of the card is in contact with the upstanding end of element E', whereby the 40 card is positioned for its respective edges to engage with the respective members E E'. The card is inserted below the cover plate, over slot b and below the plunger and the detector bar, after which plunger head 45 c^4 is struck a forcible blow, it being assumed that the card is properly positioned in the machine. The downward movement of the plunger forces the die or punch C through an edge portion of the card and opposite to 50 the time at which the card was inserted and, simultaneously with this downward movement of the plunger, stem N acts upon the detector bar M so as to produce perforations z^3 in the card along the index line z^2 55 thereon. With the card inserted face downward in the starting position, the punch or die C produces a recess w in the marginal portion of the card, and the card having been properly punched the workman re- 60 moves it from the machine and carries it

away with him. It will be understood that the workman is assigned a piece of work at the beginning of the day and is given one of the record cards, on which the date, job number, and other data should be written. 70 Having punched the card in the manner and for the purposes described the workman carries it with him and proceeds to work on the assigned job. Now when the work on the job is completed the workman proceeds 75 back to the machine and inserts the card for the second punching operation as follows: The card is placed on top of the machine and thrust beneath the cover B so that the first punch or recess w will engage with the part f of element E. This part f determines the position of the card with respect to the punch for the second punching operation, and, accordingly, the card is to be inserted 80 in such manner that the part f will substantially fill the first recess w produced in the card. The guide f being reversed to the punch, obviously, the card cannot be inserted the second time in the same position as the first insertion and still bring the recess 85 w into proper contact with guide f; accordingly, the card at the second insertion is to be reversed in position so as to secure the desired result. The card positioning member having been advanced by the time train 90 during the time intervening the first and second insertions of the card, it follows that the card when inserted the second time into the machine will occupy a different position to the punch mechanism from that which it 95 occupied during the first punching operation. Now when the punch is operated to produce the second recess w' in the card, said second recess w' occupies a reverse position to the first recess w , and the amount 100 of elapsed time will be indicated between the end of the card and the second recess w' punched in the marginal portion of said card. The card having been punched for the second time, it is removed from the machine and it serves as the basis for the 105 accounting of the value of the workman's 110 wages.

If desired the workman may be supplied with a card for each job of work, and when the particular job is completed by that particular workman said card is turned into the auditing department for the purpose of 115 keeping a record of the cost of the work and the time devoted by the workman thereto. 120 In this connection attention is called to the fact that by providing the card with a wage scale, the value of the time on each job will be computed automatically by the punching or recessing operations, for the reason that the wage value will be indicated in the scale at the same time that the scale z indicates the elapsed time. But as the workmen are paid at different rates per hour, and as it 125 may not be desirable for other workmen to 130

learn the wages paid to a particular workman, the cards may not be provided with wage scales, in which event one standard card with the elapsed time scale will be used, and these standard cards will be supplied to all workmen. The card provided with the elapsed time scale and to be punched by the operation of the machine will afford the basis for the calculation of the value of the work or the workman's wages, for the reason that the cards when punched and delivered to the auditing department can be placed in such relation to the scales on certain charts as to rapidly and accurately calculate the wage value for the particular time devoted to the job. Again, provision may be made on the card for indicating thereon the different jobs of work which are assigned to each workman for a full day's time. This requires the workman to denote the numbers of the different jobs and the character of the operations performed thereon, but the card should be punched only at the beginning of the day and one or more times according as the work on the job is completed and the work on another job is commenced.

As hereinbefore indicated the carriage with the elements E E' is impelled by the time train for a predetermined distance and at predetermined intervals controllable by the escapement mechanism, which in turn is under the control of the master clock when a series of recorders are employed on the same circuit, but the total distance traveled by the carriage and the elements E E' thereon is equal substantially to the length of the card to be inserted in the machine. Now when the carriage reaches the limit of its movement in the direction in which it is adapted to be impelled by the action of the time train, the arm K and pawl K' make practically one complete revolution, and during this travel of the carriage the spring L is placed under tension by the power of main spring G. As the carriage reaches the limit of its movement at the end of a working day the heel l of pawl K' engages with fixed post l', thus throwing the pawl out of the notch in wheel j', whereupon the notched wheel is disengaged or uncoupled from the time train and the spring L becomes effective in turning the spool, and with it the parts j j', in a reverse direction for the purpose of returning the carriage to a starting position, at which time the notched wheel will be turned by the spring L to a position ready for the nose of the pawl K' to again engage with the notch j', thereby restoring the parts to a position ready to begin operation for the next day.

It is desirable more or less frequently to equip the machine with mechanism for indicating on the cards overtime on the part of the workman, as for example, the length

of time which the workman may remain at work after the close of the working day and prior to beginning the work for the following day. The mechanism for this purpose operates in conjunction with the time train, the carriage, the releasing device, and the resetting device hereinbefore described. In addition to the mechanisms and devices described, the machine is equipped with the parts illustrated in Figs. 9, 10 and 11 of the drawings, in which figures K designates the arm with the pawl K', J is the spool provided with the notched wheel j' and the gear j, L is the spring attached to the spool and anchored at one end on the fixed post l', and J' is the rack on the carriage which is equipped with the card positioning members E E', all as hereinbefore described. O designates a second arm positioned next to arm K, said arm O being at an angle to arm K, and being fixed by the screw k' to the lower part of arbor h, whereby the arm O is adapted to operate in conjunction with arm K. On the arm O is carried a second pawl P pivoted intermediate its ends by a pin p to the arm. The nose of the pawl is provided with a stud p' which is arranged to contact with the peripheral edge of the notched wheel j' and at certain times to enter into the notch j² therein, for the purpose of making the arm O and pawl P act as a second means for connecting and disconnecting the time train with the spool J. Said second pawl P is under the control of a spring p² which acts to retain the stud p' in contact with the notched wheel j' or the notch j² therein, and the heel of this second pawl is adapted for engagement with one or the other of a group of notches or teeth provided in an escape wheel Q, the latter being carried on an arbor q mounted in the frame F'. The escape wheel is held frictionally on the arbor so that said escape wheel Q is normally at rest, but it is adapted to be operated or turned at intervals by the movement of the second pawl post and in contact with it for the purpose of presenting one of the two notches in each pair in the path of the heel of the second pawl P.

When a machine equipped with the overtime mechanism is in use, the pawl K' acts to connect the time train with the notched wheel j' on spool J in gear with the rack of the carriage, and this time train acts during the several hours of the working day to impart the desired movement to the carriage so that the cards may be punched by the workmen when operating the punching mechanism in the manner heretofore described. At the end of the working day the carriage reaches the limit of its movement, and the pawl K' is brought into engagement with the post l' so that the pawl K' will be disengaged from the notched wheel and the

8

spring L will return the carriage to a starting position, all as hereinbefore described; but at this time the following operations of the overtime mechanism take place: The escapement of the time train operates for a few minutes or other short period of time so that the pawl K' will be moved idly, but at the end of this idle period intervening the end of the working day and the beginning 10 of the overtime period, the heel of second pawl P enters the deep notch of one groove in the escape wheel, whereupon the spring γ^2 acts upon said second pawl to turn it on the pivot p so that the stud p' of said second pawl enters the notch j^2 of wheel j' , whereby 15 the arm O, the second pawl P, and the notched wheel j' operate conjointly in connecting the time train with the carriage through the geared spool J. Now, the escapement is actuated by the master clock, or 20 by other escapement mechanism, so that the time train rotates the train of arbors in order to impart movement to the carriage at predetermined intervals and for predetermined distances, and this movement of the carriage with the card positioning elements E E' enables the machine to be used after 25 the working hours or during the overtime period for the purpose of punching the time card or cards which are to be inserted into 30 the machine. The mechanism acts as described to impart movement to the carriage during the overtime period or until said carriage again approaches the limits of its 35 movement toward the finishing position, by which time the arms K O and the pawls K' P will be turned nearly one complete revolution. Now, when the heel of the pawl P is 40 brought into engagement with the fixed post γ' , said pawl is turned on its pivot and the stud p' is withdrawn from the notch j^2 in the wheel j' , whereupon the spring L becomes effective in turning the spool for a 45 limited angular distance, and the carriage is moved for a short distance toward the starting position; but before said parts can be restored to said starting position for beginning a new day's work, the pawl K' is restored into engagement with the notched 50 wheel j' in the following way: Upon the disengagement of second pawl P from the notched wheel, the spring L turns the spool backward until the notch j^2 of the wheel j' engages with the nose of pawl K'. The time 55 train now operates for a period of time intervening the end of the overtime period and the beginning of the succeeding day period so that the mechanism remains idle so far as imparting movement to the carriage is concerned. During such period, the arms K O 60 are turned and the heel of pawl P is brought into position for engagement with the shallow notch in the escapement wheel and the heel of the pawl K' engages with the fixed

post γ' so that by the continued operation of the escapement, the pawl K will become disengaged from the notch of wheel j' , thus allowing the spring L to reset the carriage to the starting position. The escapement and time train now act periodically to turn the 70 arms to a certain angular position for the purpose of shifting the pawl O by contact with the escape wheel out of engagement with said escape wheel, the pawl K' being moved far enough around for its nose to enter the notch of wheel j' , thus restoring the arm K and pawl K' to a position for again connecting the time train with the rack through the action of the spool J when the hour arrives for beginning the succeeding 80 day's work.

Having thus fully described the invention, what I claim as new, and desire to secure by Letters Patent is:

1. In a recording apparatus, the combination of a card marking member, a card positioning member, one member being movable relative to the other, and means operable by the manipulation of an inserted card for locking said movable member against 85 movement under the manipulation of said card.

2. In a recording apparatus, the combination with a card marking member, of a time operated card positioning member movable 95 relative to said card marking member, and means operable by the manipulation of a card inserted into contact with said card positioning member for locking the latter against movement.

3. In a recording apparatus, the combination with a card marking member and a card positioning member, one movable relative to the other, of frictional locking means for restraining movement of the movable member, said frictional locking means being normally inactive and brought into action solely by the manipulation of a card into contact with said movable member.

4. In a recording apparatus, the combination with a card marking member, of a time actuated card positioning member embodying locking means adapted to be brought into service solely by the manipulation of a card when inserted into contact 110 with said card positioning member for restraining the latter from movement.

5. In a recording apparatus, the combination with a card marking member, of a card positioning member, means for imparting movement to said card positioning member relative to the card marking member, and means operable by the manipulation of a card when inserted into contact with said card positioning member for restraining the 125 latter from movement.

6. In a recording apparatus, the combination with a card marking member, of a mov-

able part, a card engaging member carried by said movable part, time controlled means for imparting movement to said part with respect to said card marking member, and means operated by displacement of said card engaging member from a normal position for restraining said movable part from movement by said time controlled means.

7. In a recording apparatus, the combination with a card marking member, of a card engaging member provided with a friction lock adapted, upon the displacement of said card engaging member from a normal position, to restrain the same from movement.

15 8. In a recording apparatus, the combination with a card marking member, of a guideway, a part movable thereon, a card engaging member actuated by said movable part, and locking means coöperating with 20 said guideway and actuated by displacement of the card engaging member from a normal position for restraining said part and the card engaging member from movement.

9. In a recording apparatus, the combination with a card marking member, of a guideway, a part movable thereon, a plurality of card engaging members carried by said movable part and spaced relative to each other for the introduction of a card between them, and means operable by the displacement of one of said card engaging members from a normal position for restraining said movable part and either of the card engaging members from movement relative to the card marking device.

35 10. In a recording apparatus, the combination with a card marking member, of a carriage, a plurality of card engaging members movable with said carriage, said card engaging members being spaced for the insertion of a card into contact therewith, and means operated by the shifting of one card engaging member from a normal position for restraining said carriage from movement.

45 11. In a recording apparatus, the combination with a card marking member and a card engaging member, of detector means positioned in operative relation to the card engaging member for indicating on a card the improper insertion thereof with respect to said card engaging member.

55 12. In a recording apparatus, the combination with a card marking device and a card engaging member, of detector means operable by the card marking member for indicating on a card the improper insertion thereof relative to said card marking member.

60 13. In a recording apparatus, the combination with a card marking device, and a card engaging member, of a detector device operable by said card marking device for punching a card to indicate the proper or

improper insertion of said card relative to the card engaging member.

14. In a recording apparatus, the combination with a card marking device, and a card engaging member, of a card punching mechanism positioned in coöperative relation to said card marking device and the card engaging member whereby said card punching mechanism is effective in indicating upon the card the proper or improper positioning of said card relative to the card engaging member.

15. In a recording apparatus, the combination with a card punching device, and a card positioning member, of a movable detector member positioned in coöperative relation to said card punching device and the card positioning member, means operable by the card punching device for moving said detector member, and means actuated by the detector member for marking a card.

16. In a calculating apparatus, the combination of a recessing device adapted to punch in a card a recess of a particular form or shape, a time train, a movable guide operated or advanced by the time train in the direction of the recessing device and having the same form in horizontal cross section as the recess punched in the card by the recessing device but in reverse thereto so that when the card is punched at the expiration of a given time and reversed, the said guide will fill the recess.

17. In a calculating apparatus, a movable guide adapted to enter a recess in a record card, a time train for moving said guide, and a recessing device adapted for making a recess in the said card that will prevent said movable guide from properly entering said recess in the record card, unless the card is reversed for the second operation.

18. In a calculating apparatus, the combination of an insertible card, a card guide, a recessing device, a time train operating to advance one of the parts relative to the other, said recessing device and card guide being of such shapes in cross section, respectively, that the guide will not properly enter the recess made by the recessing device unless the card is reversed.

19. In a calculating apparatus, the combination of an insertible card, a recessing device, a time train, a movable guide operated by said time train to advance said guide in the direction of the recessing device, and a second movable guide operated by the same time train and located at a distance from the first guide substantially equal to the length of said card, the recessing device and the first mentioned guide having the same form in cross section, but one being the reverse of the other so that the said guide cannot properly enter the recess made by the recessing device unless said card is reversed.

20. In a recording apparatus, the combination with a card marking device, of a card positioning member, a carriage therefor, a time train for imparting movement to said carriage, and means for automatically returning the carriage to a starting position.

21. In a recording apparatus, the combination with a card marking device, of a carriage, a card positioning member thereon, a time train for imparting movement to said carriage, means for connecting and disconnecting the time train with said carriage, and tension means for returning said carriage to a starting position, said returning means being placed under tension by the operation of the time train.

22. In a recording apparatus, the combination with a card marking device, of a carriage, a card positioning member thereon, a time train for imparting movement to said carriage, means for connecting and disconnecting the time train with said carriage, means for tripping said connecting and disconnecting means to release the carriage from the time train, and means for returning the carriage to a starting position.

23. In a recording apparatus, the combination with a card marking device, of a clock operated member, and means for automatically re-setting said member and for operating the same to adapt the recorder for use during overtime working hours as well as for use during regular working hours.

24. In a recording apparatus, the combination with a card marking device, and a clock operated card positioning member, of means for automatically resetting said card positioning member to a starting position, means whereby said card positioning member is operated for indicating on a card the

periods of overtime work, and tripping means for rendering inactive the overtime means.

25. In a recording apparatus, the combination with a card marking device, and a card positioning member, of a time train, a feed pawl and disk for connecting the time train with said card positioning member, means for releasing the feed pawl, means for resetting the card positioning member to starting position, and a second feed pawl for engagement with said disk and for connecting the time train with the card positioning member so that the latter may be used for indicating overtime work on inserted cards.

26. In a recording apparatus, the combination with a card marking device, and a card positioning member, of a time train, a feed pawl and disk for connecting the time train with said card positioning member, means for releasing the feed pawl, means for resetting the card positioning member to starting position, a second feed pawl for engagement with said disk and for connecting the time train with the card positioning member so that the latter may be used for indicating overtime on inserted cards, and an escape wheel coöperating with the second pawl for shifting it into and out of engagement with said disk at stated periods of time.

In testimony whereof I have signed my name to this specification in the presence of two subscribing witnesses.
